UNITED STATES PATENT OFFICE.

CHARLES THOMAS BOWERS, OF PERTH AMBOY, NEW JERSEY.

MEANS TO RAISE SUNKEN VESSELS.

1,188,888.

Specification of Letters Patent. Patented June 27, 1916.

Application filed December 24, 1915. Serial No. 68,514.

To all whom it may concern:

Be it known that I, CHARLES T. BOWERS, a citizen of the United States, and a resident of Perth Amboy, in the county of Middlesex and State of New Jersey, have invented a new and Improved Means to Raise Sunken Vessels, of which the following is a full, clear, and exact description.

This invention relates to ships and has particular reference to means providing for the rescue or recovery of stranded submarines or sunken vessels of any other type.

More definitely stated, the primary object of the invention is to equip a submarine boat with one or more, preferably a plurality of, devices each including a casing secured to or built within the hull of the boat and having its outer end adapted to be opened to the sea to admit sea water for the purpose of buoying from the casing a float which, rising to the surface of the water, will carry with it a line through which a heavy power cable may be secured for the manipulation of the stranded boat or vessel.

Another object of the invention is to provide a special form of brace for the interior of the hull of a submarine or other boat, the same constituting an anchorage means or connection for the power cable above referred to as well as serving to counteract or resist the crushing strains to which the hull is subjected.

A further object of the invention is to provide a buoyant cap or cover for the casing, the same being normally held in closing position by a plurality of jack screws which, because of their peculiar support, serve to positively lift or start the cap from closing position when the casing is to be opened to the sea.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a diagrammatic view indicating a sunken or stranded submarine boat equipped with my improvement, the floats being indicated as having risen to the sur-

face of the water in position to be picked up by a rescuing ship; Fig. 2 is a vertical sectional detail of one of the casings complete in its normal position and indicating the upper end of the above mentioned brace; and Fig. 3 is a cross sectional detail on the line 3—3 of Fig. 2.

Referring now more particularly to the drawings I show at 10 a conventional form of submarine boat or submarine as it will be hereinafter referred to. By this expression, furthermore, I wish to be understood as covering broadly any sea-going vessel adapted to have my improvements attached as a permanent part of its equipment.

At 11 is indicated a casing having a practically closed bottom 12 and an open top or outer end surrounded by a laterally projecting securing flange 13 through which, by means of lag bolts 14 or their equivalent, the casing is secured rigidly and permanently against the inner surface of the deck of the submarine.

The casing is shown preferably of cylindrical form and has a downwardly projecting central neck 15 in which the upper end eye 16 of an anchor brace 17 is located. A packing gland 18 surrounds the upper end of the brace and is secured tightly to the lower end of the neck 15. A collar 19 is secured to the brace against the lower surface of the gland by means of a pin 20 or its equivalent. The head or eye portion of the brace rests snugly against the structure of the neck on the inside and the gland and collar devices make rigid connection on the outside of the neck and thereby the casing structure as a whole and brace are locked in fixed position with respect to each other. The brace is strong and rigid and has its lower end secured rigidly at 21 to the bottom portion of the submarine. The brace, therefore, serves two important functions; first, it acts as one of the internal braces for the submarine, resisting crushing strains tending to collapse the submarine, and, secondly, by virtue of the connection, above described, with the casing and also with the bottom of the submarine, upward draft upon the eye 16 is distributed between the casing and the bottom of the submarine.

The power cable 22 above referred to is secured at one end to the eye 16 and to its other end is secured a comparatively light line 23 whose other end is secured at an eye 24 to a float 25 of any suitable size, form

or material, of sufficient strength to resist crushing strains and possessed of sufficient buoyancy to float readily to the top of the water from any reasonable depth and carry with it the light line 23 when released from the casing.

At 26 I indicate a cap made preferably of wood or some other buoyant material, the same serving normally to close the opening 10 27 formed through the deck of the submarine, and adjacent or registering with which is the flanged portion of the casing. The bottom of the cap includes or consists of a metal plate 28 adapted to make watertight 15 connection with the deck and through which the cap is secured in position by means of a plurality of jack screws 29 shown as four in number and journaled in ears 30 adjacent the lower end of the casing and also 20 in the flange 13 at the upper end of the casing. Each jack screw is provided with fixed collars 31 which bear respectively against the upper face of the ear 30 and the lower face of the flange 13 whereby such 25 screw is held from endwise movement but permitted to be rotated freely in either direction by means of a hand wheel 32 or its equivalent at its lower end. The upper or outer ends of the screws project into 30 sockets 34 formed in the cap 26 and have threaded engagement with nuts 35 located in such sockets by rotation of the screws in one direction. The action of the nuts is to lock the cap firmly in watertight position 35 upon the deck, this operation being done preparatory to setting forth on the voyage or while the casing is empty of water. Each of the screws is rotated in this manner until the connection through its nut is secure.

40 The operation of the improvement may be briefly summarized as follows: In the event of the submarine becoming stranded or disabled beneath the surface of the water, and it is desirable to make communication with 45 a rescue party at the surface of the water, any person within the submarine, upon rotating the jack screws in a releasing direction, will cause the cap to be forcibly released from its set position against the ex-

ternal pressure tending to hold the cap seated, the screws, being held from endwise movement, constituting power screws with a lifting effect. When the screws are thus turned loose from the cap nuts and the cap having been lifted to admit water into the casing and thereby establish equilibrium of the pressures above and below the cap, the cap will be free to float away and the float will be buoyed promptly to the surface of the water carrying the light line 60 with it. It is preferable to equip each submarine with two or more of these devices whereby power applied to the power cables 22, which may be drawn up by means of the light line, will effectively recover the disabled submarine.

I claim:—

The combination with the deck of a submarine having an opening therethrough, of a rigid hollow cylindrical casing having its 70 inner end substantially closed and its other end open and provided with a laterally projecting flange bearing against the under surface of the deck around said opening, means extending through the flange locking the 75 casing in fixed position with respect to the deck, said casing having a series of outwardly projecting ears having holes therethrough and the flange being provided with holes in alinement with the respective ear 80 holes, a series of jack screws journaled in the alined holes of the ears and flange, means to prevent endwise movement of the screws but permitting free rotation thereof in said 85 holes, a cap on the outside of said deck opening, a series of nuts carried by the cap and cooperating with the outer threaded ends of the screws and serving when the screws are turned in one direction to bind the cap against the deck and in the other direction 90 to positively free the cap from the deck, and means carried normally within the casing adapted to be floated to the surface of the water when the cap is removed.

CHARLES THOMAS BOWERS.
